UNITED STATES PATENT OFFICE.

OSCAR A. SMITH, OF CLEVELAND, OHIO, ASSIGNOR TO THE NATIONAL ACME COMPANY, OF CLEVELAND, OHIO, A CORPORATION OF OHIO.

ROTARY MILLING AND SLOTTING MACHINE.

1,374,962.

Specification of Letters Patent. Patented Apr. 19, 1921.

Application filed July 9, 1919. Serial No. 309,641.

To all whom it may concern:

Be it known that I, OSCAR A. SMITH, a citizen of the United States, residing at Cleveland, in the county of Cuyahoga and 5 State of Ohio, have invented certain new and useful Improvements in Rotary Milling and Slotting Machines, of which the following is a specification.

This invention relates to metal working 10 machines, and more particularly to that class thereof known as milling and slotting machines, the object of the invention being to provide an improved machine of this class capable of doing heavy milling or slotting 15 by the continuous milling process.

The present improved machine is a horizontal type machine, that is, it is built horizontally and has the following improvements:

20 A work spindle or shaft secured to and driving the work holding disk, which shaft is substantially as large in diameter as the work holding disk, and receives its power at the periphery thereof by means of a 25 worm driven worm wheel substantially as large as the work holding disk. By means of this construction vibration of the shaft and the consequent chattering of the work or tool are practically eliminated. Not only 30 this, but distortion or weaving of the work relative to the cutter are also eliminated. A fixed cutter shaft powerfully back-geared, one of which shafts is adjustable toward and from the other, and in the organization 35 shown, the back-geared cutter shaft is a fixed shaft while the work shaft is adjustable toward and from the cutter by means of an adjustable carrier or slide having a bored bearing for the reception of the relatively 40 long, large diameter work shaft, the speed of the work carrying disk and cutter being regulated independently. In addition, the peculiar organization of the gearing for rotating the cutter and the work shaft is such 45 that the cutter can be run at a maximum speed and the work disk at a minimum speed, which, together with the particular organization of the work holding shaft and its correlated parts, has resulted in an im- 50 proved milling and slotting machine where- in, notwithstanding the very high speed of the cutter relative to the work, there is no vibration of the work or weaving thereof, and no chattering of the tool relatively 55 thereto.

One of the great advantages of this improved machine is that by reason of its construction and organization a much heavier cut can be made with the cutter running at a slower speed than has heretofore been possible, thus prolonging the life of the cutter. It has been found in practice that one of these machines will practically do the work of twelve standard milling machines, and not only this, but that 60 the cutters will wear longer and the production be very materially increased.

It is a well known fact that in the operation of the ordinary milling machine on heavy cuts, there is so much noise made 70 by the cutter due to the excessive vibration and chattering, that it is practically impossible to hear the human voice anywhere near the machine when it is running, while the present improved machine during the running thereof is almost noiseless, conclusively proving that the vibration and chattering has practically been eliminated by reason of this improved organization of mechanism, 75 there being no difficulty in carrying on conversation close to the machine in an ordinary tone of voice.

One of the problems arising in this machine which had to be worked out and which required considerable study was that of running the cutter at the maximum speed and the disk at the minimum speed with the least amount of mechanism and a one-belt drive, which important object is accomplished in the present machine in which 80 the spindle is powerfully back-geared.

Heretofore in all machines of this type one of the difficulties has been to eliminate the chattering of the tool cutter on the work and which has been a serious drawback to 85 production. In the present construction however, the machine is absolutely rigid due largely to the fact that the relatively long shaft is directly driven at the periphery thereof through the medium of a worm 90 wheel secured to said shaft adjacent to the end thereof opposite to the work holding disk, and which worm wheel is substantially as large as the work holding disk while the shaft has a large diameter relatively to the 95 work holding disk and its worm wheel, so that the work carrying disk does not project sufficiently beyond its shaft to cause distortion or weaving of the work relatively to the cutter and the frictional resistance of 100 105 110

the long, large diametered shaft relatively to its large bearing is also such that the vibration or chattering of the work and the weaving of the work relatively to the cutter 5 are practically eliminated.

In the drawings accompanying and forming a part of this specification, Figure 1 is a perspective view illustrating the front or feeding side of the machine; Fig. 2 illustrates the rear or driving side thereof; Fig. 3 is a plan view partly in section of the machine; Fig. 4 is a cross sectional view taken on line 4—4 Fig. 3; Fig. 5 is a cross sectional view taken on line 5—5 Fig. 3; Fig. 6 is a front side view of the machine illustrating a part of the cutter shaft mechanism in section; Fig. 7 is a perspective view of the work holding spindle, the cutter shaft and the driving mechanism or gearing for actuating these parts; Figs. 8 and 9 are front and side views respectively of the work holding disk, Fig. 8 illustrating the cutter adjacent thereto; Fig. 10 is a detail view of two pieces of work and the clamp 25 which may be used for holding the work in position on the disks, the dotted lines indicating the milled portions; and Fig. 11 shows a completed piece of work, it having been reversed in the disk and the opposite 30 end milled away.

Similar characters of reference indicate corresponding parts in the several figures of the drawings.

In the preferred form thereof shown, the bed 2 of the machine is mounted on a pan 1, which is provided with an oil reservoir. The bed 2 carries a dove-tailed part or guide 3 on which is mounted a slide 4 held in position by means of a suitable key 5 and adjustment screws 5' (see Fig. 6). At right angles to this dove-tailed guide 3 of the bed 2 the slide 4 is provided with a suitable bore in which is mounted or housed a hollow disk relatively long, large diametered shaft 45 6. Secured to the rear of shaft 6 is a worm gear 7 in the form of a ring having a series shown in the present instance as 6 projections or lugs 7' for the reception of a similar number of screws or bolts by means of 50 which the ring gear is clamped or secured to the hollow shaft 6 (see Fig. 1). Directly under this worm gear 7 and at right angles with the shaft 6 and mounted in suitable bearings in the bed 2 is housed a worm shaft 55 8, on which is mounted a worm 9 carried by a sleeve 9' to which one of the change speed gears 50 hereinafter described is secured, and which worm is in mesh with the worm gear 7. A suitable change speed system 60 of gearing and disconnecting clutch mechanism 50 are located against the side of the bed 2 and are partly carried at the outer end of the worm shaft 8 and by a stub shaft secured to the side of the bed, a handle 51 65 for manipulating the clutch being provided.

In an extended housing 52 of the bed 2 and secured to worm shaft 8 is a spur gear 10. Mounted in the extended housing 52 above and parallel with the worm shaft 8 is an auxiliary shaft 11 to which is secured a 70 spur gear 12 in mesh with spur gear 10. Secured to this auxiliary shaft 11 adjacent to one end thereof and against the inner face of the extended housing 52 is a beveled gear 13, at the outer side of which is secured a 75 collar 14. Extending at right angles to the auxiliary shaft 11 and mounted in suitable bearings of the extended housing 52 and a similar housing 53 of the bed 2 is another shaft 15, one end of which carries a beveled gear 16 in mesh with the beveled gear 13. To the opposite end of this shaft 15 and located in the extended housing or bearing 53 is secured a spur gear 17 in mesh with a spur gear 19 carried by an auxiliary shaft 80 18 likewise suitably mounted in the housing 53. On this same shaft 18 and adjacent to spur gear 19 is a spur gear 20, which is in mesh with a spur gear 22 carried by a shaft 21 in alignment with shaft 15. One end of 85 this shaft 21 is supported in the extended housing 53 of the bed 2 while the other end thereof has a bearing in and passes through another extended housing 54 carried by the bed 2, while the inner end of this shaft 21 90 rests against the face of spur gear 17. Secured to the shaft 21 within the housing 54 is a spur gear 23 in mesh with a spur gear 25 carried by a cutter spindle 24, which is located at a suitable angle above and parallel with shaft 21, the spur gear 25 being suitably housed in the extended bearing or housing 54.

To the outer end of the cutter spindle 24 is mounted cutter arbor 26 by means of a 105 suitable taper, such as is used in milling machines. A suitable cutter 26' is mounted on the arbor in the usual way, viz: with collars and locknut and the cutter arbor has an outer support in an arbor support bracket 110 27, which is carried by the housing 53 by means of a suitable tongue and bolts. On the outer end of the shaft 21, which may be designated as the main driving shaft, is secured a suitable belt pulley 28, which is 115 shown as a three-speed pulley. To the end of the work carrying spindle or shaft opposite to that to which the worm gear 7 is fastened is secured work disk 29, it being observed that this shaft and work disk are 120 of substantially the same size. This work disk is machined to suit the work that is to be milled and the set screws 29' (see Fig. 9) clamp in conjunction with the clamps 29'' the work in position to be milled. For adjusting the slide 4 and the work carrying disk 6 toward and from the cutter a suitable screw 30 and hand wheel 31 are provided, the screw being suitably mounted in the slide 4 and on the bed 2 (see Fig. 5). 125

130

From the foregoing, it will be observed that power being imparted to the pulley 28 on the main driving shaft 21, such power is transmitted from spur gear 28 to spur gear 5 25 and thereby drives the cutter spindle 24 and thereby the cutter arbor 26 and the cutter 26' to revolve the cutter in the direction of the arrow shown in Fig. 7. At the same time power is also transmitted from the 10 shaft 21 to the spur gear 22 and from thence to gears 20, 19 and 17 to drive the shaft 15, which by means of the beveled gearing 13 and 16 drives spur gear 12 and gear 10 on the worm shaft 8, which in turn by means 15 of change speed gearing 50 drives the worm 9 and thereby the worm wheel carried by the work spindle or shaft 6, the speed of the shaft 6 being regulated by the change speed gearing 50.

20 A suitable oil pump 39 is carried by the bed 2 and is driven by a pair of gears 40 and 41, the gear 40 being secured to the pump shaft while the gear 41 is carried by and receives its power from the auxiliary 25 shaft 18.

In the operation of the machine, a suitably formed work carrying disk is mounted on the work carrying shaft or spindle 6 and a suitable cutter is mounted on the arbor 26, 30 the work being held in position on this disk by means of either a set screw or a swivel clamp according to the character of the piece of work to be operated upon.

The speed of the cutter in relation to the 35 speed of the work carrying disk varies, and this is taken care of by means of the three-speed pulley 28 and the change gear system, the three-speed belt pulley regulating the speed of the cutter while the change-gear 40 system regulates the speed of the work carrying disk. The work carrying disk feeds toward the cutter, *i. e.* rotates downwardly while the cutter rotates away from or upwardly as indicated by the arrows in 45 Fig. 7.

The depth of the cut is regulated by the adjustable screw and hand wheel 31. By means of the system of four spur gears 17, 19, 20 and 22 in connection with the worm 50 and worm wheel and change gear system 50 the speed of the work carrying disk may be reduced to the minimum required for anything that can be milled in this machine.

The present improvement enables the cutter 55 to be run at a maximum speed and the work carrying disk at the minimum speed, with the least amount of mechanism and a one-belt drive, which as hereinbefore stated, was a problem which required considerable

60 study before it was worked out.

It of course will be understood that the various details may be more or less changed without departing from the spirit or scope of the invention as expressed in the claims.

65 Referring to Fig. 9, the work carrying

disk comprises what may be considered as the milling chuck, which is in the form of a ring 29 constructed to fit over a projecting portion of the revolving shaft and is secured thereto by suitable screws so that this 70 work disk or chuck will have a bearing upon the revolving shaft. In other words, the revolving shaft may have a forwardly projecting flange while the work disk or chuck may have a rearwardly projecting 75 flange, one fitting over the other, so that the chuck will have a bearing upon the end of the shaft. To this work disk or chuck is suitably secured a clamping ring or milling chuck ring 29'', it being so designed that it 80 will fit into the milling chuck 29 and likewise has bearing therein and is secured thereto by suitable screws. The set screws 29' carried by the milling chuck ring or work holding disk serve to secure the clamps 85 29'' against the work which in turn hold the work in the spaces provided in the chuck 29. The chuck or work holding disk and the clamping or milling chuck ring may be considered as forming the work holding 90 means or work holding disk.

The "to and fro" movement and also the "up and down" movement of the cutters and the work when this is present is familiarly known to mechanics as "weaving" and this 95 is the meaning of the term as used herein, and it is this weaving which the present improvement eliminates.

I claim as my invention:

1. In a milling and slotting machine, the 100 combination of rotary work holding means, a rotary shaft of relatively large diameter carrying said work holding means, a rotary cutter supported at one side of said shaft, means for feeding said work holding shaft 105 sidewise toward and from the cutter, and means for rotating the cutter and shaft and including a single belt driven differential speed pulley, the shaft at a low speed as compared with the high speed of the cutter. 110

2. In a milling and slotting machine, the 115 combination of rotary work holding means, a rotary shaft of relatively large diameter carrying said work holding means, a rotary cutter supported at one side of said shaft, means for feeding said work holding shaft sidewise toward and from the cutter, means for rotating the cutter and shaft, the shaft at a low speed as compared with the high speed of the cutter, said last means comprising a single belt differential pulley-driven shaft, a direct drive therefrom to the cutter, and an indirect drive to the work holding shaft. 120

3. In a milling and slotting machine, the 125 combination of a rotary work holding disk, a rotary shaft carrying said work holding disk and of large diameter relatively thereto whereby the disk does not extend sufficiently beyond the shaft to cause distortion or weav- 130

ing of the work relatively to the cutter, a rotary cutter, means for operating said shaft and cutter comprising a direct drive to said cutter, and a variable indirect drive to said shaft, said cutter being rotated at high speed as compared to the low speed of the work holding means.

4. In a milling and slotting machine, the combination of a rotary work holding disk, 10 a rotary shaft carrying said disk and of large diameter relatively thereto whereby the disk does not extend sufficiently beyond the shaft to cause distortion or weaving of the work relatively to the cutter, a rotary cutter, a fixed shaft for supporting the same, means for operating said shafts comprising a powerful back-geared direct drive to the cutter shaft, and a variable indirect drive to said work shaft, said cutter being rotated at 15 a high speed as compared to the low speed of the work holding means, and means for shifting said rotary work shaft toward and from the cutter.

5. In a milling and slotting machine, the combination of rotary work holding means, a 20 rotary shaft of relatively large diameter carrying said work holding means, a rotary cutter supported at one side of said shaft, means for feeding said work holding shaft sidewise 25 toward and from the cutter, means for rotating the cutter and shaft, the shaft at a low speed as compared with the high speed of the cutter, said last means comprising a differential pulley belt driven shaft, a direct drive 30 therefrom to the cutter, an indirect drive to the work holding shaft, said indirect drive comprising a system of spur gears, worm 35 wheel mechanism, and change speed gearing, said work holding shaft having the power 40 transmitted thereto at the periphery of the rear end.

6. In a horizontal type milling and slotting machine, the combination of a work holding disk, a rotary shaft secured thereto 45 and having substantially the same diameter as said work holding disk, a rotary cutter, means for rotating said cutter, and means for supporting said work holding shaft for movement toward and from the cutter, and 50 means for rotating said work holding shaft.

7. In a horizontal type milling and slotting machine, the combination of a work holding disk, a rotary shaft secured thereto and having substantially the same diameter 55 as said work holding disk, a rotary cutter, means for rotating said cutter, and means for supporting said work holding shaft for movement toward and from the cutter, and means for rotating said work holding shaft, 60 said means including a worm and worm wheel, the latter carried by and at the rear of said work holding shaft.

8. In a milling and slotting machine, the combination of a work holding disk, a shaft 65 for driving the same having substantially

the diameter of said disk, means for transmitting power to the periphery of said shaft, a rotary cutter carrying spindle, means for adjustably supporting said disk and shaft for movement toward and from the cutter, 70 and means for regulating the speed of the cutter and of the work carrying disk independently.

9. In a milling and slotting machine, the combination of a work carrying disk, a shaft 75 therefor having substantially the same diameter as said disk, means for driving said shaft at the periphery thereof and comprising a system of spur gears, worm wheel mechanism, and change gear mechanism.

10. In a milling and slotting machine, the combination of a work carrying disk, a hollow shaft therefor having substantially the same diameter as said disk, means for driving said shaft at the periphery thereof and comprising a system of spur gears, worm 80 wheel mechanism, and change gear mechanism, said worm wheel mechanism comprising a ring worm wheel secured to the rear end of said hollow shaft.

11. In a milling and slotting machine, the combination of a work carrying disk, a shaft 85 therefor having substantially the same diameter as said disk, means for driving said shaft at the periphery thereof and comprising a system of spur gears, worm wheel mechanism, change gear mechanism, a cutter carrying spindle, and means for driving said spindle in the same direction as said shaft, the main driving means for said spindle and the work carrying shaft being primarily the same.

12. In a milling and slotting machine, the combination of a bed, a dove-tailed guide thereon, an adjustable slide mounted on said bed, means for adjusting said slide, a work carrying disk, a shaft carrying said disk and having substantially the same diameter as said disk and carried by said adjustable slide, and means for driving said shaft at 105 the periphery thereof.

13. In a milling and slotting machine, the combination of a bed, a dove-tailed guide thereon, an adjustable slide mounted on said bed, means for adjusting said slide, a work carrying disk, a shaft carrying said disk and having substantially the same diameter as said disk and carried by said adjustable slide, means for driving said shaft at the periphery thereof and comprising a worm 110 wheel mechanism, a system of change gears, a system of spur gears, a differential belt pulley driven shaft for driving said spur gears, a cutter driving shaft, and means for driving the same from said belt driven shaft.

14. In a milling and slotting machine, the combination of a work holding disk, a hollow shaft for driving the same having substantially the diameter of said disk, a slide 130

- for supporting said shaft, means for adjusting said slide transversely of the axis of said shaft, a worm wheel carried at the peripheral rear end of said shaft, a worm 5 in engagement with said worm wheel, a crosswise extending shaft carrying said worm, change speed gears located at one end of said last shaft, an auxiliary shaft, spur gears between said auxiliary shaft and worm shaft, a shaft extending transversely of said auxiliary shaft, bevel gears between said last shaft and auxiliary shaft, a main driving shaft, a differential speed belt pulley at one end thereof, a shaft extending in parallelism with said main driving shaft, a set 10 of spur gears between said main driving shaft, said last shaft and said bevel gear shaft, a cutter shaft, and spur gears between said main driving shaft and cutter shaft.
- 15 15. In a milling and slotting machine, the combination of rotary work holding means, a rotary shaft therefor of relatively large diameter, a cutter carrying shaft, means for feeding one of said shafts transversely of the axis thereof relatively to the other, a primary driving shaft, gearing comprising a small gear carried by said primary driving shaft and a large gear carried by said cutter shaft, and a system of speed reducing 20 gearing between said primary driving shaft and said rotary work shaft whereby the cutter shaft is rotated at a high speed and the work holding shaft at a low speed.
- 25 16. In a milling and slotting machine, the combination of rotary work holding means, a rotary shaft of relatively large diameter, means for feeding said shaft transversely of the axis thereof, a cutter driven shaft, means for rotating the cutter at a high speed 30 and for rotating the work holding shaft at a low speed and comprising a primary driving shaft, and means for rotating it at different speeds.
- 35 17. In a milling and slotting machine, the combination of rotary work holding means, a rotary shaft of relatively large diameter, means for feeding said shaft transversely of the axis thereof, a cutter driven shaft, means for rotating the cutter at a high speed 40 and for rotating the work holding shaft at a low speed and comprising a primary driving shaft, and means for rotating it at different speeds.
- 45 18. In a milling and slotting machine, the combination of rotary work holding means, a rotary shaft of relatively large diameter, means for feeding said shaft transversely of the axis thereof, a cutter driven shaft, means for rotating the cutter at a high speed 50 and for rotating the work holding shaft at a low speed and comprising a primary driving shaft, means for rotating it at different speeds, said primary driving shaft carrying means for rotating the cutter shaft and also 55 means for imparting rotation to the work holding shaft, said last means comprising a system of spur gears, a worm wheel mechanism, and a change gear mechanism, said worm wheel mechanism comprising a ring worm wheel carried at the peripheral rear end of the work holding shaft.
- 60 19. In a milling and slotting machine, the combination of rotary work holding means, a rotary shaft having substantially the same 65 diameter as and carrying said work holding
- means, a rotary cutter supported at one side of said shaft, means for feeding said cutter and shaft one relatively toward and from the other, and means for rotating the cutter and shaft, one at a low speed and the other 70 at a high speed.
19. In a milling and slotting machine, the combination of rotary work holding means, a rotary shaft having substantially the same diameter as and carrying said work holding 75 means, a rotary cutter supported at one side of said shaft, means for feeding said cutter and shaft one relatively toward and from the other, and means for rotating the cutter and shaft, the shaft at a low speed and the 80 cutter at a high speed.
20. In a milling and slotting machine, the combination of a work holding disk, a shaft for driving the same having substantially the diameter of said disk, means for transmitting power to the periphery of said shaft, a rotary cutter carrying spindle, means for adjustably supporting said disk and shaft for sidewise movement relatively one to the other, and means for regulating the speed 85 of the cutter and of the work carrying disk independently.
21. In a milling and slotting machine, the combination of a work carrying disk, a shaft therefor having substantially the same diameter as said disk, means for driving said shaft at the periphery thereof and comprising a system of spur gears, worm wheel mechanism, change gear mechanism, a main driving shaft, a differential belt pulley mounted 90 on said main driving shaft, a cutter carrying spindle, means for driving said spindle, the main driving means for the spindle and for the work carrying shaft being primarily the same, the speed of the work carrying 95 shaft being regulated by the change gear system and the speed of the cutter carrying spindle by the belt pulley, and means for feeding said shaft and cutter carrying spindle sidewise one relatively to the other. 100
22. In a machine of the class described, the combination of a rotary shaft, work holding means secured thereto, a worm wheel also secured thereto, said shaft having a diameter substantially as large as the 115 worm wheel and work holding means, means for rotating said shaft through said worm wheel, a cutter shaft, a cutter thereon, means for rotating said cutter shaft, and means for shifting said worm wheel shaft and cutter 120 shaft one relatively to the other.
23. In a machine of the class described, the combination of a shaft, work holding means secured thereto at one end, a worm wheel also secured thereto at its opposite 125 end, said shaft having a diameter substantially as large as the worm wheel and the work holding means, means for rotating said shaft through said worm wheel, a cutter shaft, a cutter thereon, means for rotating 130

said cutter shaft, the rotating means for the cutter shaft and the worm wheel shaft comprising a primary driving shaft, and means for shifting the worm wheel shaft 5 and cutter shaft one relatively to the other.

24. In a machine of the class described, the combination of a rotary shaft, work holding means secured thereto, a worm wheel also secured thereto, said shaft having 10 a diameter substantially as large as the worm wheel and work holding means, means for rotating said shaft through said worm wheel, a cutter shaft, a cutter thereon, means for rotating said cutter shaft, means for 15 shifting said worm wheel shaft and cutter shaft one relatively to the other, and means for varying the speed of the worm wheel shaft relatively to that of the cutter shaft.

25. In a milling and slotting machine, 20 the combination of a work holding disk, a relatively long shaft carrying said disk, supporting means having a bearing for receiving said shaft, a rotary cutter, means for rotating the cutter, means for shifting 25 the cutter and work shaft relatively to each other, gearing for rotating the work holding shaft and including a peripheral gear adjacent to the end opposite to said disk and having a diameter substantially the 30 same as the work holding disk, said shaft having a large diameter relatively to said disk and peripheral gear whereby the frictional resistance thereof is increased relative to its bearing and the chattering or 35 vibration and weaving of the work relatively to the cutter are practically eliminated.

26. In a milling and slotting machine, the combination of a work holding disk, a relatively long shaft carrying said disk, supporting means having a bearing for receiving 40 said shaft, a rotary cutter, means for rotating the cutter, means for shifting the cutter and work shaft relatively to each other, gearing for rotating the work holding shaft and including a peripheral gear adjacent to the end opposite to said disk and having a diameter substantially the 45 same as the work holding disk, said shaft having a diameter substantially as large as said disk and peripheral gear whereby the frictional resistance thereof is increased relative to its bearing and the chattering or 50 vibration and weaving of the work relatively to the cutter are practically eliminated, the means for rotating the cutter and work holding disk being so organized as to rotate the cutter at a high speed and the disk at a relatively slow speed.

60 27. In a machine of the class described, the combination of a shaft, work holding means secured thereto, a worm wheel also secured thereto, said shaft having a diameter substantially as large as said worm wheel 65 and work holding means, means for rotat-

ing said shaft through said worm wheel and comprising a primary driving shaft, and a system of reducing variable speed gears between said primary shaft and said worm wheel, a cutter shaft, a cutter thereon, 70 means for rotating said cutter shaft, and gearing between said primary driving shaft and said cutter shaft, and means for shifting the worm wheel shaft and the cutter shaft one relatively to the other. 75

28. In a machine of the class described, the combination of rotary work holding means, a rotary shaft therefor of relatively large diameter, a cutter shaft, means for feeding one shaft toward and from the 80 other, a primary driving shaft, gearing between said primary driving shaft and cutter shaft, and a system of reducing speed gearing between said primary driving shaft and work holding shaft. 85

29. In a machine of the class described, the combination of a primary driving shaft, a single belt driven differential speed pulley thereon, a small diameter spur gear secured to said shaft, a cutter shaft in parallelism 90 with said driving shaft, a large diameter spur gear secured to said cutter shaft and in mesh with said small spur gear, a cutter secured to said cutter shaft, a rotary work holding shaft in parallelism with said primary driving and cutter shafts, work holding means and a worm wheel carried by said last shaft, the said work holding shaft, work holding means and worm wheel all having substantially the same diameter, a 100 worm shaft extending transversely of the work holder shaft and having a worm in mesh with said worm wheel, gearing connecting said worm shaft and primary driving shaft and including variable speed 105 gears, and change speed gearing for the worm shaft.

30. In a machine of the class described, the combination of a primary driving shaft, a single belt driven differential speed pulley 110 thereon, a small diameter spur gear carried by said primary driving shaft, a cutter shaft in parallelism with said primary driving shaft, a large spur gear secured thereto and in mesh with said small spur gear, a cutter 115 secured to said cutter shaft, a rotary work holding shaft in parallelism with said driving and cutter shafts, work holding means and a worm wheel carried by said last shaft, said work holding shaft, work holding 120 means and worm wheel all having substantially the same diameter, a worm shaft extending transversely of the work holding shaft and having a worm in mesh with said worm wheel, an auxiliary shaft parallel 125 with and gear-connected to said worm shaft, a shaft in alinement with said primary driving shaft and gear-connected with said auxiliary shaft, and variable speed gearing between said primary driving shaft and its 130

aligned shaft, the organization being such that the cutter is driven at a high speed and the work holding shaft at a low speed, said speeds being variable relatively to each other.

31. In a machine of the class described, the combination of a rotary shaft, work holding means secured thereto, a worm wheel also secured thereto, said shaft having 10 a diameter substantially as large as the worm wheel and work holding means, means for rotating said shaft through said worm wheel, and including a pair of shafts, one extending transversely to said rotary 15 shaft and the other transversely to said last

shaft and projecting beyond said rotary shaft, a cutter shaft having the major part thereof likewise projecting beyond said rotary shaft and in parallelism with that part of said shaft which projects beyond said rotary shaft, a cutter on said cutter shaft, means for rotating said cutter shaft at a speed greater than the speed of the rotary shaft, and means for shifting said rotary shaft and cutter shaft one relatively to the other. 20 25

Signed at Cleveland, county of Cuyahoga and State of Ohio, this 3rd day of July, 1919.

OSCAR A. SMITH.
